APPLIANCE FOR HEATING SYSTEMS

Stephen Jencick and Homer L. Schneider,
Chagrin Falls, Ohio

Application October 19, 1934, Serial No. 749,004

4 Claims. (Cl. 237—68)

This invention relates to the art of heating systems and may be applied to a heating system employing either steam or vapor.

Heretofore, in either of the systems just referred to, there has been experienced considerable difficulty because of the presence of air in the system. This has caused what may be known as an "air-lock" which has prevented efficient operation of the system. In order to get rid of this air in the pipe line so as to break this "air-locked" or "air-bound" condition, it has been common practice to rely upon an increase in temperature in the system. This, however, has obviously involved additional cost of fuel and also decreased efficiency in the operation of the system. The presence of air in the system retards the raising of the temperature and prevents proper regulation and control of the same.

The object of the present invention is to provide a means for automatically and directly relieving this objectionable air condition in the heating system and for producing the proper degree of vacuum therein for maximum efficiency.

Another object is to devise such a system in which the air condition is relieved by a means other than by increasing the temperature which has heretofore been relied upon for this purpose. Accordingly, this invention contemplates an automatic control means whose actuation is governed by the presence of air in the system for relieving such air condition.

Another object is to combine with our air-controlled means an auxiliary temperature-controlled means so as to co-ordinate with each other in relieving the air condition in the system; and also to construct such a combined control device in the form of a self-contained unit which may be readily applied as an attachment to a system already installed.

A further object is to devise such an attachment which can be manufactured and sold at a comparatively low price and which is dependable and not apt to get out of order.

Other objects will be apparent from the following description and claims when considered together with the accompanying drawings.

Fig. 1 is a top plan view of our present improved device;

Fig. 2 is a vertical, longitudinal sectional view taken on line 2—2 of Fig. 1;

Fig. 3 is an end view of our device;

Fig. 4 is a detail view taken on line 4—4 of Fig. 2; and

Fig. 5 illustrates the manner in which our de-

vice is assembled as part of an otherwise conventional heating system.

It is to be understood that the present disclosure is merely for purposes of illustration and that various modifications may be made without departing from the spirit of the present invention as herein set forth and claimed.

In the accompanying illustrations, the present device is shown installed in a conventional form of heating system which is indicated only partially but which will be fully and clearly understood by those who are familiar with the art of heating systems. In this system, the boiler 1 has the main distributing pipe line 2 which is connected with the individual radiators 3 through 10 the risers 4. The return pipe 5 also has connections to the other side of the radiators 3. As indicated in Fig. 5, the present device is connected to the return pipe 5 at a point in the basement. Thus, one of these devices may be employed in 20 connection with the heating system of an entire building, or individual devices may be provided for separate heating systems that heat different sections of a building.

Our present improved unit has a threaded projection 6 for connection to the joint member 7 in the return pipe 5. The projection 6 is integral with the head 8 of the housing of the device and the other part 9 of the housing is secured thereto by means of the screw bolts 10 which engage the 30 overlying flanges 8^a and 9^a, respectively. The flange 8^a terminates in the right-angular flange 8^b.

Between the flanges 8^a and 9^a, there is clamped the edge portion of the flexible diaphragm 11 which is mounted at its center in the grooved member 12. The part 12^a of the grooved member 12 may be formed separately from the other part 12^b and maintained in assembly by the nut member 13^c which is threaded onto the projection 13 as a matter of convenience in assembling the 40 diaphragm 11. The member 12 has an axially disposed projection 13 provided with a passage 14 communicating at its one end with the valve chamber within which the ball valve 15 is housed for seating engagement with the end of passage 45 14 for closing the same, or for permitting the same to be open. This valve chamber opens into the space within the housing 9, that is, on the right-hand side of diaphragm 11, as viewed in Fig. 2. These parts are so constructed and arranged that the diaphragm 11 may be moved back and forth and air forced through the passage 14 and the communicating valve chamber and dispelled out through the apertures 16 in the housing wall 9.

The force with which the air is withdrawn is not sufficient to withdraw the comparatively small quantity of water of condensation from the return pipe. Furthermore, this device is so located and arranged as to minimize this danger, as indicated in Fig. 5, and further precaution may be provided if deemed necessary, as for instance the inclusion of a trap at this point.

Suitable means is provided for maintaining the ball valve 15 within its chamber, as for instance, the plug 15^a which has its edge slotted so as to always permit passage therethrough as these slots will not be closed by ball 15.

Upon the left-hand side of the diaphragm 11, as viewed in Fig. 2, the coil spring 17 is mounted co-axially with respect to the projection 13 and abuts at its one end against the nut member 12^c. The other end of spring 17 bears against the central valve disk 19 which is adapted to close the central opening 20 in the web or wall 21 formed integral with the head member 8. The disk 19 has its edge notched, as indicated at 19^a, and has a centrally disposed projection for centering engagement within the end of spring 17. The opening 20 is comparatively small and may be effectively closed by engagement of the disk 19 thereover under pressure of spring 17. Upon release of the disk 19, there will be a passage through the opening 20 and around the notched edge of disk 19 to the chamber between the head 8 and the diaphragm 11.

At the other or left-hand side of opening 20, there is a chamber 22 formed in the head, this chamber having communication with the return pipe 5 through the projection 6 and also with the chamber 23.

A flexible diaphragm 24 extends across the top of chamber 23 and is secured at its center portion to the lower end of rod 25, while the edge of diaphragm 24 is secured in an air-tight manner to the wall of the auxiliary housing 26. This securing means consists of a screw-threaded ring 27 which holds the edge of the diaphragm in engagement with the integral flange 28, a gasket being provided between the ring and the diaphragm, as illustrated in Fig. 2. The other end of rod 25 has the abutment 29 for one end of coil spring 30 which at its other end abuts an apertured disk 31 having screw-threaded engagement 50 with the wall of the housing 26. The central portion of the disk or ring 31 is upturned about the aperture therethrough and the spring 30 engages thereabout for centering the same. The ring 31 may be adjusted in order to vary the tension of spring 30 and any suitable means may be provided for locking the ring 31 in set position.

The upper end of the rod 25 is provided with the electric insulation disk 32 which is adapted to engage the electric switch member 33 for closing an electric circuit with the companion contact 34. The member 33 is in the form of a spring finger mounted on the electric terminal 35 which in turn is mounted in the top 36 of electric insulation which has screw-threaded engagement 65 with the upper end of the chamber wall 26 for closing the same. The contact 34 is part of the electric terminal 37 which is also mounted in the top 36.

The terminals 35 and 37 are in the circuit 38 which is connected to the main electric supply line and includes also the small electric motor 39, the electric terminal 40 and the thermostatically controlled means for automatically opening and closing the circuit through the terminal 40. This terminal is mounted in electric insulation in

the wall of the housing 9 and has a contact member 41 extending therefrom for co-operation with the bi-metallic thermo-couple 42 which is adapted to engage the contact 41 for closing the circuit, the one end of the couple 42 being connected with the circuit 38. This thermo-couple is mounted upon electric insulation 42^a within the housing 9 and its upper end extends through an opening 43 in the wall of the housing.

The motor 39 is mounted in one end of the housing 9 by means of the clamps 44 and is adapted to rotate the worm 45 on the shaft 46 which has bearing at its other end in the wall of the housing 9. The worm 45 meshes with the gear 47 which is mounted in the housing 9 and which operates the rod 48 through the crank connection 49. The other end of rod 48 is pivotally connected to the grooved member 12 for operating the diaphragm 11.

It will be observed that the switch at the terminal 40 will be opened or closed according to the temperature produced by the heating system and there may be placed a radiator in the basement of the building so that the thermo-control means may respond to a temperature corresponding with that of the main part of the building. If there be a difference between the temperatures of the basement and the remainder of the building, this difference may be taken into account and the thermo-couple may be adjusted accordingly so as to render the same operable with respect to the temperature desired for the main part of the building. Or, if so desired, the thermo-couple and the switch controlled thereby may be located elsewhere in the building but still in the circuit 38.

It will also be observed that the switch 33-34 is adapted to be opened or closed according to the absence or presence of air in the pipe line. That is, if there be air in the line and hence in the chamber 23, the spring 30 will be permitted to close this switch; but if there be a vacuum in the line, or an absence of air, the force of this vacuum will overcome the force of the spring and will cause this switch to be opened, through the operation of diaphragm 24 and the parts associated therewith.

The effect of both switches being closed is to operate the motor 39 which causes movement of the diaphragm 11 back and forth with a pump action to draw air from the pipe line and from the chamber 23. As the diaphragm 11 is drawn towards the right (Fig. 2), the valve disk 19 will be raised from its seat and air will be drawn past the same while the valve 15 remains closed upon its seat so as to close the passage 14. Then as the diaphragm 11 is forced towards the left, (Fig. 2), the valve disk 19 will be closed and held closed and the air which has been drawn into the chamber between the head 8 and diaphragm 11, will be forced through the passage 14 and past the valve 15 which is thereby forced open.

Thus, it will be seen that with air in the pipe line, the circuit will be closed through the motor 39, assuming that the presence of air in the line has caused such lowering of the temperature as to effect a closing of the switch by the thermostatic control means. It is to be understood that the thermo-couple is so constructed and arranged that a decrease in temperature below a predetermined point, will cause the switch to be closed, and an increase in temperature above the predetermined point, will cause this switch to be opened. Assuming both the air-controlled and thermo-controlled switches to be closed, the mo-

tor 39 will be operated and the air in the pipe line will be withdrawn therefrom and dispelled out through the openings 16, this operation continuing until a predetermined degree of vacuum is produced for which the spring 30 has been set. Then the force of suction of the vacuum thus established will cause the switch 33-34 to open and the motor 39 to stop. With the "air-bound" or "air-locked" condition in the system thus removed, the heat supplied from the boiler may be effective in producing the desired temperature throughout the system.

If the temperature in the system should at any time rise to a point beyond that for which the thermostat is set and before the air has been removed from the system to the point of automatically opening the switch 33-34, the circuit will be automatically broken by the thermostat so as to stop the motor and thereby prevent any further vacuum from being formed in the system. And if the temperature of the system should still remain above the predetermined point when the switch 33-34 might be closed by the presence of air in the system, the motor 39 could not begin to operate until the temperature should fall below the predetermined point for which the thermo-couple is set.

Thus, with our device, the conditions existing in the heating system at any given time with respect to temperature and presence or absence of air in the system, are regulated automatically and individually. No longer is it necessary to rely upon increased temperature to overcome the effect of air in the system and to thereby require an increased consumption of fuel, as has heretofore been necessary. As a result, the obtaining and maintaining of the desired temperature may be accomplished with a decided saving in fuel as compared with the prior practice; and furthermore, the present device renders the system more conducive to obtaining and maintaining any desired degree of temperature, whereby there is realized a decided acceleration in the speed with which the desired temperature may be obtained.

Therefore, the segregation of the factors of temperature control and regulation of the air or vacuum condition results in an increased efficiency in the operation of the heating system and also a reduction in cost of such operation.

This device is in the form of a unitary attachment which can be manufactured and sold as such and applied to any heating system which has already been installed. Also, the cost of this device is comparatively low.

What we claim is:

1. In the art of the class described, a unitary attachment adapted to be connected to the return pipe of a heating system, said attachment comprising a housing and a reciprocatable diaphragm arranged within said housing and dividing the same into forward and rearward compartments, said housing having means of connecting said forward compartment to the return pipe, said connecting means constituting the only means of connection for said attachment, valve means actuated by said reciprocatable diaphragm for permitting air to be withdrawn from the pipe line into said forward compartment upon movement of said reciprocatable means in one direction and to be discharged to said rearward compartment upon movement of said reciprocatable diaphragm in the other direction, and means controlled by the presence of air in the system and by the temperature of the system for operating said reciprocatable diaphragm, said air control means and

temperature control means being carried by and forming a part of said unitary attachment.

2. In the art of the class described, a unitary attachment adapted to be connected to the return pipe of a heating system, said attachment comprising a housing and a reciprocatable means arranged within said housing and dividing the same into forward and rearward compartments, said housing having means of connecting said forward compartment to the return pipe, said connecting means constituting the only means of connection for said attachment, valve means actuated by said reciprocatable means for permitting air to be withdrawn from the pipe line into said forward compartment upon movement of said reciprocatable means in one direction and to be discharged to said rearward compartment upon movement of said reciprocatable means in the other direction, said attachment comprising also an auxiliary housing forming part thereof and having communication with the return pipe and adapted for communication with said forward compartment, means within said auxiliary housing and controlled by the presence of air therewithin for effecting operation of said reciprocatable means, and thermo-responsive means coordinated with said air responsive means in controlling the operation of said reciprocating means, said thermo-responsive means being carried by said first-named housing.

3. In the art of the class described, a unitary attachment adapted to be connected to the return pipe of a heating system, said attachment comprising a housing and a reciprocatable flexible diaphragm arranged within said housing and dividing the same into forward and rearward compartments, a one-way valve connection between the return pipe and said forward compartment and a one-way valve connection between the forward and rearward compartments, said valve connections being so arranged that air may be withdrawn from the return pipe into the forward compartment by movement of said diaphragm in one direction, and then discharged from the forward compartment to the rearward compartment by movement of the diaphragm in the other direction, means for reciprocating said diaphragm, said attachment comprising also an auxiliary housing forming part thereof and having communication with the return pipe and adapted for communication with said forward compartment, means within said auxiliary housing including a flexible diaphragm responsive to the presence or absence of air in said auxiliary housing for automatically controlling the operation of said reciprocating means, and a thermo-responsive means carried by said first-named housing and co-ordinated with said air-responsive means in controlling the operation of said reciprocating means.

4. In the art of the class described, a unitary attachment adapted to be connected to the return pipe of a heating system, said attachment comprising a housing and a reciprocatable, flexible diaphragm arranged within said housing and dividing the same into forward and rearward compartments, a one-way valve connection between the return pipe and said forward compartment and a one-way valve connection between the forward and rearward compartments, said valve connections being so arranged that air may be withdrawn from the return pipe into the forward compartment by movement of said diaphragm in one direction, and then discharged from the forward compartment to the rearward compartment.

by movement of the diaphragm in the other direction, means for reciprocating said diaphragm, and a thermo-responsive means carried by said housing for controlling the operation of said reciprocating means, said attachment comprising also an auxiliary housing forming part thereof and having communication with the return pipe and with said forward compartment, and means within said auxiliary housing including a flexible diaphragm responsive to the presence or absence 10 of air in said auxiliary housing for co-ordinating

with said thermo-responsive means in controlling the operation of said reciprocating means, said reciprocating means including an electric motor carried by said first-named housing, and said co-ordinated control means including an electric circuit therefor with switches carried by said housings and adapted to be opened and closed by said thermo-responsive and air-responsive means. 5
